VICTOR H. HARBERT, OF CHICAGO, ILLINOIS, ASSIGNOR TO ILLINOIS RAILWAY EQUIPMENT COMPANY, OF CHICAGO, ILLINOIS, A CORPORATION OF ILLINOIS

LOCKING MEANS

Application filed July 3, 1931. Serial No. 548,562.

My invention relates to means, more especially intended for fastening or locking the hatch covers of a railroad refrigerator car, although the means may be equally as well employed for locking other devices in place.

My invention has for its object the provision of a hook type of lock whereby the hatch cover may be locked in closed position 10 and the usual types of car seals employed; while at the same time the improved means may be employed for holding the hatch cover in car ventilating position when desired.

My invention contemplates locking means 15 wherein the locking element is so secured to or so associated with the hasp member of the locking means as to become an integral part thereof after the latter has been secured in place on the hatch closure that disassociation 20 of the respective members is prevented.

As a result, my improved locking element will at all times be held in place where it may be readily moved or shifted to locking position.

25 The objects and advantages of my invention will be readily comprehended from the detailed description of the accompanying drawings, wherein:

Figure 1 is a top plan view of a hatch 30 closure and portion of a car-roof, with my improved locking means in locking position.

Figure 2 is a transverse sectional view with the locking means shown in elevation in locked position.

35 Figure 3 is a plan view of my improved locking means in unlocking position and showing, in dotted lines, the manner of assembling; a portion of one end being in section.

40 Figure 4 is a sectional view taken substantially on the line 4—4 of Figure 3.

Figure 5 is a plan view of a modified form of the locking means, shown in unlocking position.

45 Figure 6 is a longitudinal section of same.

Figure 7 is a plan view of another modified form of my invention, shown in locking position.

50 Figure 8 is a sectional view of a portion of a different type of hatch closure of a re-

frigerator car provided with the type of locking means shown in Figure 7 and in locking position.

Figure 9 is a front side elevation thereof.

The hatch closures or covers of refrigerator 55 cars are generally locked in closed position by the employment of a hook secured to the hatch cover by a chain; the hook being intended to pass through a suitable staple on the car-roof after the hasp member has been put

into position. Considerable difficulty and expense has been encountered with this type 60 of locking means because the hooks are loose and therefore free to become engaged with the running boards on the car roof when the

hooks are in unlocking position and the hatch 65 covers have been swung to complete open position; the chains permitting the hooks at the ends to shift about on the car-roof. As a

result, these hooks and chains are often torn 70 loose from the hatch cover when the operator swings the heavy hatch cover to closed position and as a result the hook members become lost. With the conditions just mentioned,

aside from tearing the hook loose from its fastenings, the sheathing of the hatch closure 75 also frequently becomes torn loose or damaged, and as a result considerable renewal and repair expense is encountered by the railroads in the maintenance of refrigerator cars.

Furthermore, with the present type of fastening means, where the hooks are secured to the hatch closures by chains, the hook and free end of the chain frequently swing im- 80

properly beneath the closure member while the latter is being swung into closed position, with the result that the hinges of the closure 85 member become strained, while the closure member frequently becomes tightly wedged in partial closed position necessitating the same to be pried loose.

My invention is designed to overcome these serious objections and in its specific embodiment as disclosed in the first four figures of the drawings comprises the hasp member 15, 95 which is intended to be secured to the top of the hatch closure member or cover 16.

The hasp member 15 comprises a suitable casting having the straight body portion 17 provided with suitably positioned openings 100

to receive the fastening bolts 18 whereby the hasp is secured to the cover 16 adjacent to the free or unhinged side thereof, as shown in Figures 1 and 2; the cover being shown 5 hinged at 19 to the car-roof, so as to swing clear of the hatch when desired.

The unattached end 20 of the hasp 15 extends beyond the hatch cover as shown in Figure 2 and this end is preferably bifurcated 10 as shown at 21 in Figure 3 and the bifurcated end disposed in the upwardly inclining manner shown in Figures 2 and 4. In order to afford ample strength to the bifurcations and also to receive one end of the lock member, the 15 hasp is shown provided with the upstanding longitudinal webs 22, 22, arranged along opposite sides of the hasp at the end 20, as more clearly shown in Figure 4.

The bifurcated or slotted portion of the 20 hasp is intended to receive the usual L-shape lever 23 which is secured to the car-roof adjacent to the hatch, by means of the staple and link as at 24 in Figure 2, in order to permit the lever 23 to swing between the bifurcations 25 and over the top of the hatch-cover 16, as shown, when the cover is locked in full closed position.

The lever 23 is generally provided with a plurality of spaced holes as at 25, for the purpose of holding the cover 16 in a desired 30 raised position for purposes of ventilation and also to receive the locking member when in closed position.

My improved locking means involves the 35 U-shape hook member 26; one side or leg whereof, namely leg 27, is somewhat shorter than the other side or leg 28. This hook member is preferably circular in cross-section.

40 The web portions 22, 22 are provided with aligned openings 29 adapted to receive the leg 28 of the hook member and permit it to slide back and forth therein. The holes 29, at one side, namely the side disposed toward 45 the bifurcated end of the hasp, are each provided with the intersecting slot 30, see Figure 4.

The long leg 28 of the hook member at its 50 end is provided with a laterally disposed lug 31, which corresponds with the slot 30 and therefore permits the end or leg 28 of the hook member 26 to be inserted through the openings in the hasp member during assembly of the locking means.

55 As shown in Figure 3, the distance between the plane of the end of short leg 27 and the plane of the lug 31 of the hook member 26 is less than the combined width and spacing of the bifurcations 21 of the hasp member, with 60 the result that after the hook member has been put into place, the free end of the leg 27 of the hook member will extend or remain in the hole of one of the bifurcations, as shown in Figure 3, because the lug 31 will then be 65 out of register with the slot portion 30 and

therefore prevent further outward sliding movement of the hook member.

The hook member 26 is made of suitable metal which will permit it to be bent as shown in dotted lines in Figure 3, before assembly, 70 thus enabling the leg 28 with its lug 31 to be inserted through the opening 29, after which the short leg 27 is then bent back to the normal position shown in full lines and therefore into the aligned holes 32 in the 75 bifurcations 21, 21 of the hasp.

It is apparent that after the hasp and hook members have been assembled as just described, withdrawal of the hook member 26 from the hasp 15 is impossible, because the 80 lug 31 on the leg 28 of the hook member 26 is arranged to extend upwardly at a distance removed from the slot portion 30 of the opening in the hasp. The lug 31 is constantly maintained in the upwardly disposed direction shown in dotted lines in Figure 4 because the short leg 27 of the hook member at all times remains in the hole 32 of one of the 85 bifurcations 21 of the hasp and hence prevents rotation of the hook member about 90 its axis.

The leg 27, of the hook member 26, adjacent to its end, is provided with an opening extending transversely therethrough; the opening preferably in the nature of a slot 95 as shown at the sectioned end at 33 in Figure 3; and leg 28, of the hook member, intermediate of its ends, namely in alignment to opening 33 in leg 27, is also provided with an opening extending transversely therethrough 100 and preferably in the nature of a slot as shown in dotted lines at 34 in Figure 3.

These slots are intended to receive the usual seal as indicated at 35 in Figure 1, which may be in the nature of a wire or a 105 strip of sheet metal which is passed through both slots and then bent back so the two ends may be united with the usual solder or sealing material, as shown at 36 in Figure 1.

The locking means, as shown in Figure 110 3, is in the maximum unlocking condition, namely in position to release the lever 23, because the end of the short leg 27 of the hook member is disposed entirely within the hole 32 of one of the bifurcations of the hasp, 115 as shown in dotted lines, thus permitting free movement of the lever 23 between the bifurcations 21 of the hasp 15. To lock the hatch cover, the lever 23 is swung between the bifurcations of the hasp, either into the position shown in Figure 2, when the hatch cover 16 is to be in full closed position, or into a position where any one of the holes 25 of the lever 23 will register with the holes 32 in the bifurcations 21 of the hasp 15, at 120 which time the hook member is slid toward the opposite side of the hasp, thus causing the short leg 27 of the hook member to pass through the hole in lever 23 which has been brought into register. The lengths of the 125

legs 27 and 28 of the hook member are such that the slots 33 and 34 will then be positioned on the opposite side of the hasp from that shown in Figure 3, where the slots will 5 be in the clear to receive the usual seal.

It is apparent from the construction shown and described, that the slot portions 30 of the openings 29 in the hasp are merely employed during insertion of the hook member; 10 but after the leg 28 with its lug 31 has been inserted completely into place, the hook member is swung upwardly and the short leg 27 is then bent back parallel with leg 28 and the end of leg 27 forced into the hole 32, thus moving lug 31 out of register with the slot portion 30 of openings 29. Withdrawal of the hook member 26 is then impossible.

Where my improved locking means is to 20 be applied to equipment at present in use, the same hasp member, shown at 37 in Figures 5 and 6, which is on the refrigerator car may be used. This hasp member 37 is generally secured on the hatch cover by means 25 of two bolts, as shown at 38; the free end of the hasp member being inclined upwardly as shown and this inclined portion 39 provided with the closed ended slot 40, which receives the lock lever 23. The upstanding 30 portion 39 is provided with the aligned openings 41.

In order to apply my invention to such hasp, I provide the small hook holding plate or member 42, a portion whereof is flat and 35 adapted to extend flush with the top of the hasp 37 and this portion apertured to receive one of the bolts 38 whereby the hasp is secured to the hatch cover. The member 42 is shown somewhat vertically enlarged at 40 one end and the lower face of this enlargement socketed, as shown at 43, to receive the long leg 44 of the hook member 45 and permit sliding movement thereof.

The long leg of the hook member 45 is 45 shown provided with an enlargement or head 46 which prevents withdrawal of the hook member. This hook member 45, like hook member 26, is also provided with a short leg 47 adapted to be slidably mounted in the 50 hole 41 of the inclined portion 39 of the hasp; with the length of leg 47 such that the distance between the end of leg 47 and the head 46 of leg 44 is less than the transverse width of the inclined portion 39 of the hasp member. 55 As a result, it is apparent that after assembly, hook member 45 cannot be withdrawn and the short leg 47 will at all times be in position for immediate movement to locking position after the desired hole 25 in lever 23 has been aligned with the short end 47.

In the locking means shown in Figures 5 and 6, the short leg 47 is first inserted into the opening 41 and the long leg 44 disposed 60 across the main portion of the hasp 37 at the

base of the inclined portion 39; the clip or holding member 42 is then placed over the long leg 44 of the hook member 45 and secured in place by one of the bolts 38, as shown. 70

Like in the previously described construction, the hook member 45 is constantly in proper position to be moved through the desired hole in the lever 23 for locking the hatch cover; while accidental removal of the hook member is impossible. 75

The hook member 45, like hook member 26, also has each leg provided with the registering openings or slots disposed transversely through both legs as shown in dotted lines at 34 in Figure 5; the slots 34 being arranged so they will be disposed on the opposite side of the hasp member from that shown in Figure 5, so as to be in the clear to receive the usual sealing element generally employed, as for example the type shown in Figure 1, and which prevents movement of the hook member back to the unlocking position shown in Figure 5. 80

In Figures 7 to 9, I illustrate my improved locking means applied to a different type of hatch closure which is more especially used on certain types of refrigerator cars generally employed for meat shipment, namely a cover which is not hingedly secured in place. In this type of refrigerator car, one end of the hatch cover is disposed beneath the running board on the car-roof and the locking lever 23 is not employed. In this type of hatch closure, one end of the cover 48 (which normally is disposed in spaced relation with the roof and overhangs the side of the hatch is shown in Figure 8) is provided with the angularly bent, or somewhat Z-shape hasp 49. One end of the hasp is secured on top of the hatch cover 48 by bolts as at 50, with the intermediate portion of the hasp 49 depending at the forward end of the cover; while the free, horizontally disposed end of the hasp is intended to be disposed substantially parallel with the car-roof A. 95

This free end of the hasp is provided with a slot to receive the staple member 51 which is bolted or otherwise secured to the car-roof as shown. 100

The hook member 52, which may be similar to hook member 45, is slidably secured in place by the clip or holding member 53, somewhat similar to clip member 42, except that it has a top flat face adapted to fit flush with the lower side of the overhanging end of the hatch cover 48, and a flat vertical side adapted to fit flush against the intermediate vertically disposed portion of the hasp 49. The vertically disposed face of the clip member 53 is socketed as shown at 54 for slidably receiving the long leg of the hook member 52 and which leg has the enlargement or head 55 which prevents withdrawal of the hook member. The short leg of the hook member is adapted to pass through the eye of the 115 120 125 130

staple member 51 after the end of the hasp 49 has been passed over the staple as shown.

In this construction, the short leg of the hook member is shown provided with a diagonally arranged slot or opening disposed transversely through the short leg as shown in dotted lines at 56, Figures 7. The arrangement of the slot 56, as will be seen in Figure 7, is such that portions of the slot 56 will be disposed on opposite sides of the staple 51 when the hook member 52 is in locking position, thus permitting the usual sealing wire or sealing element to be passed through the slot and the ends of the wire or element then soldered or sealed together in the usual manner, thus preventing withdrawal of the short end of the hook member from the staple 51 without breaking the seal.

The construction shown in Figures 7 to 9, like the construction shown in Figures 5 and 6, may readily be applied to equipment in use without change in construction, as the clip member 53 is provided with a vertically disposed aperture to receive one of the bolts 50 which fasten the hasp to the hatch cover; the hook member, like in the other constructions, being permanently secured in place and carried by the hasp member which is secured to the hatch cover.

That is to say, in all of the forms of my invention herein disclosed, the hook members are slidably secured to and carried by the hasp members of the hatch closure, either as an integral part, so to speak, or as a supplemental and detachable part; the hook members being held in intimate relation with the hasp and therefore at all times following the position of the free end of the hatch cover; with the hook members firmly held against accidental removal and hence free of the objections of damage and loss heretofore encountered with the locking means at present in use.

I have shown what I believe to be simple embodiments of my invention which have been described in terms employed merely as terms of description and not as terms of limitation, as structural modifications are possible without, however, departing from the spirit of my invention.

What I claim is:

1. Locking means of the character described comprising an elongated hasp member one end whereof is inclined upwardly and bifurcated, the bifurcations at the outer ends having registering openings and at a point removed from the outer ends having registering openings and slots communicating with said openings; and a U-shaped hook member whose legs are of unequal length, the long leg at its end being provided with a laterally disposed portion corresponding with said slots in the hasp so as to permit insertion of the long leg into said openings with the slots, said slots being disposed in a

direction beyond the swinging movement of the hook member when the hasp is secured in place and withdrawal of the hook member made impossible, the legs of the hook member being provided with aligned sealing medium receiving openings whereby sliding movement in the hasp is prevented when the hook member is in locking position.

2. Locking means of the character described comprising an elongated hasp member, one end whereof is bifurcated to receive an apertured latch member therebetween; the hasp member having registering openings at the outer end and communicating openings and slots removed from the first mentioned openings; and a U-shaped hook member whose legs are of unequal length and arranged to slide in the openings in the hasp member, the long leg of the hook member being provided at its end with a laterally disposed lug adapted to initially pass through the slots before the short leg enters its corresponding openings in the hasp member, with the length of the long leg of the hook member and positioning of the lug being such that withdrawal of the short leg from the openings in the hasp member beyond latch member releasing position is impossible.

3. Locking means of the character described comprising an elongated hasp member, one end whereof is bifurcated to receive an apertured latch member therebetween, the hasp member having registering openings at the outer end and non-circular openings removed from the outer end; and a U-shaped hook member whose legs are of unequal length and arranged to slide into said openings, the long leg at its end having a laterally disposed lug adapted to initially pass through the non-circular openings, the lug being arranged to be out of register with the non-circular openings when the short leg has entered the openings at the ends of the bifurcations, with the distance between the lug and the plane of the end of the short leg of the hook member being such that complete withdrawal of the short leg of the hook member from its openings in the hasp member is impossible; the end of the short leg and an intermediate portion of the long leg being provided with aligned sealing medium receiving openings.

VICTOR H. HARBERT.
